UNITED STATES PATENT OFFICE.

FRED W. LEUTHESSER, OF CHICAGO, ILLINOIS.

STEAM, AIR, AND WATER TRAP VALVE.

1,102,768.

Specification of Letters Patent.

Patented July 7, 1914.

Application filed July 30, 1913. Serial No. 782,080.

To all whom it may concern:

Be it known that I, FRED W. LEUTHESSER, a citizen of the United States, residing at Chicago, in the county of Cook and State 5 of Illinois, have invented certain new and useful Improvements in Steam, Air, and Water Trap Valves, of which the following is a specification.

This invention relates to return line 10 valves for use in steam heating systems; and to that class of such valves employing a float for controlling the discharge of the water of condensation; and the invention belongs to the special type of float valves or 15 traps which permit the air to vent and the water of condensation to discharge, without allowing the escape of but little, if any, of the steam.

It has been found in practice that return 20 line valves or traps must be noiseless in operation for steam heating systems installed in public halls and buildings, as otherwise, more or less annoyance or discomfort arises from the noise produced 25 either by a faulty construction of, or an imperfect operation of the valves or traps, or other cause. Return line valves or traps are noise producers for two main causes: the contact of the float or some part carried 30 thereby with the surrounding shell or casing, which results in a constant clicking sound that is annoying and nerve racking, or the failure of the float to rise and fall properly for opening and closing the dis- 35 charge port or passage, thereby failing to relieve the heating unit of the water of condensation and the air, thus causing a hammering in the heating unit, which is exceedingly annoying and disagreeable.

In the present invention the difficulty is 40 eliminated by providing a horizontal cross plate, partition or diaphragm, dividing the interior or chamber of the shell or casing into an upper and lower compartment, the 45 upper compartment to serve as a float chamber and the lower compartment to serve as a water receiving and discharging compartment, enabling a lower or bottom inlet for the water of condensation to be utilized, 50 without any ill effects from the flow of the water into and out of the float chamber.

The objects of the present invention are 55 to construct a valve or trap for the return line of steam heating systems that will be of simple construction, perfect in operation, operate in a noiseless manner, vent the air

and discharge the water of condensation automatically, and prevent the escape of steam in a wasteful manner; and which can be readily taken apart for cleaning and repairs; and will not become easily clogged; will discharge without creating any agitation of the water of condensation around the float that would interfere with or impair the movements of the float; will furnish a body 60 of still water in which the float is free to rise and fall as the water rises and falls around the float; will prevent any sudden inrush of water against the float; will cause the water to have a gentle, gradual upward 65 and downward flow around the float, which will give the float a steady and uniform rising and falling movement, by which hammering in the heating unit and any sound 70 producing contact or click of the float with the surrounding metal parts will be obviated and overcome to an extent that will not render the operation of the valve or trap 75 annoying and objectionable.

In the drawings: Figure 1 is a sectional 80 elevation of a return line valve or trap embodying the present invention; Fig. 2 a similar view of Fig. 1, showing a modified form of the lower water receiving and discharging chamber, and showing also a modified 85 form of the horizontal cross-plate, separating the upper and lower compartments of the valve or trap; Fig. 3 a plan view of the horizontal cross-plate, of Fig. 1; Fig. 4 a plan view of the horizontal cross-plate, 90 of Fig. 2; Fig. 5 a plan view of a modified form of horizontal cross-plate, and Fig. 6 a plan view of another modified form of horizontal cross-plate.

The valve or trap as shown has an outer 95 shell or casing 13, with a lateral neck 14, adjacent to its lower end. The neck 14 has an exterior screw thread to receive a coupling nut 15, having an inner end flange or rim 16 to engage a flange or rib 17 on the 100 exterior of a nipple or tailpiece 18, with an axial or longitudinal passage 19, for the nut 15 and nipple 18 to form a coupling for attaching the valve or trap to the radiator or other heating unit or device, and the passage 19 to furnish one section of an inlet for the water of condensation to enter the valve or trap. The bottom wall 20 of the shell or casing 13, in the arrangement shown, has a depending neck 21 with a hole 105 22 forming the outlet for the trap or valve; and as shown the hole 22 is screw threaded 110

for attaching the valve or trap to a return pipe, or other discharging means.

The neck 14 has a passage 23 in communication with the passage 19 and forming the inlet for the water of condensation to enter the interior of the shell or casing so that the shell or casing is provided with an outlet 22 and an inlet 23 for the water of condensation to flow into and be discharged from the valve or trap.

The inlet 23 is deflected downward by a wall or abutment 24 located, as shown, in line with the wall of the shell or casing, which wall or abutment, in the arrangement of Fig. 1, extends across the longitudinal path of the inlet 23, and in the arrangement of Fig. 2 extends around in the plane of the wall of the shell or casing. This wall or abutment 24 in conjunction with the inlet 23 forms a species of goose-neck trap, which, when the water of condensation rises above the lower edge of the wall or abutment 24, furnishes a stoppage or dam against the passage of steam to any appreciable extent into the interior of the outer shell or casing.

The inlet 23 leads or opens into a lower compartment or chamber 25, at the bottom of the interior of the outer shell or casing, and constitutes a water receiving and discharging chamber, above which is an upper compartment or chamber 26, constituting a float chamber. The compartment or chamber 25, as shown in Fig. 1, is substantially of the same diameter as that of the compartment or chamber 26, while as shown in Fig. 2, the lower portion of the wall of the shell or casing 13 is outflared so as to form an extension 25^a of the compartment or chamber 25, giving an increased capacity for the compartment or chamber 25 and furnishing an air space that will assist in the discharge of the water quickly, and at the same time providing a safeguard against any sudden rush of water from entering the float chamber too rapidly or in a manner to affect the float in its operation.

The lower compartment and the upper compartment are separated one from the other by the horizontal cross-plate, 27, so constructed as to allow the water of condensation to flow from the lower receiving and discharging chamber into the upper float chamber, when the discharge valve is closed and to flow from the upper float chamber into the lower receiving and discharging chamber for final discharge when the discharge valve is open. The flow into, and the flow out of, the upper float chamber must be quiet and gentle, and for this purpose the horizontal cross-plate, must be constructed so as to furnish communication between the lower compartment 25 and the upper compartment 26 that will permit a flow of water back and forth between the

two compartments without any agitation of the water in the upper compartment, maintaining a still body of water in the upper compartment and giving the float a gentle rising and falling movement.

The horizontal cross-plate, in one form of construction is shown in Figs. 1 and 3; another modified form of construction is shown in Figs. 2 and 4, other modified forms of construction are shown in Figs. 5 and 6, and other forms can be utilized, providing the constructions are such as to furnish a horizontal separation and a free communication between the two compartments or chambers by which a still body of water will be maintained in the upper compartment or float chamber and water will be supplied to and discharged from the float chamber in such a manner as to give a gentle and quiet rising and falling movement to the float.

The horizontal cross-plate 27 of Figs. 1 and 3 has a large central hole 28 and a series of openings 29, and extending partly over each opening is a deflecting tongue or lip 30, each tongue having an upward and outward inclination by which water passing through the opening 29 will be deflected outward and upward toward the wall of the shell or casing and away from direct contact with and impingement against the bottom of the float. The horizontal cross-plate, 27 of Fig. 5 has the central hole 28 and a series of small holes 29^a, adjacent to the periphery thereof, so that water passing through the series of holes 29^a will not contact with and impinge against the bottom of the float. The cross-plate, 27 of Figs. 2 and 4 has the central hole 28 and has a diameter less than the diameter of the upper compartment so as to leave a space 29^b between the edge of the cross-plate, for water to flow into and out from the upper compartment without directly contacting with or impinging against the bottom of the float. The cross-plate, 27 of Fig. 6 has the hole 28 and a series of notches or openings 29^c in the peripheral edge, which allow water to flow into and out from the upper compartment or chamber out of direct contact with or impingement against the bottom of the float.

It is preferred to have the communication, between the upper compartment or chamber and the lower compartment or chamber so arranged as not to have the water act or impinge direct against the bottom of the float, but such communication whether by holes, or perforation, or a space, or otherwise could be arranged more or less underneath the bottom of the float, if so desired.

The cross-plate, 27, as shown in Figs. 1 and 3, rests on or is supported at its periphery on a ledge or flange 31, inwardly projecting from the wall of the outer shell or casing, and as shown in Figs. 2 and 4,

is unsupported at its periphery. A plug 32 is entered into the hole 28 of the cross-plate 27 and has a shoulder 33 against which the plate, abuts. A ring nut 34 threads on the 5 plug 32 and holds the cross-plate, attached and carried by the plug. The lower end 35 of the plug 32 is screw threaded and entered into a screw threaded hole in the bottom wall 20 of the outer shell or casing, so that 10 when the plug 32 is entered into position, the cross-plate, is properly located to divide the lower compartment or chamber 25 from the upper compartment or chamber 26, and to also enable the cross-plate, to be easily 15 removed for cleaning or other purposes, it only being necessary to unscrew the plug 32 from its connection with the bottom wall 20, which permits the plug, and with it the cross-plate, to be withdrawn through the upper 20 per end of the shell or casing.

The plug 32 is formed with lateral or side ports or passages 36, which ports or passages are located at a point adjacent the floor of the casing and in communication with these passages 36 is a vertical port or passage 37, extending through the end of the plug and opening into the hole 22 of the neck 21, for the passages 36 and passage 37 to form an outlet from the lower compartment 25, by 25 which the water of condensation in such compartment will be discharged therefrom and be partially discharged from the upper compartment 26, when the passage 36 is open to permit the water of condensation to 30 escape from the lower chamber.

A float 38 is located and operates in the upper compartment 26 and, owing to the still body of water maintained in this compartment, the float 38 at all times has a 35 gentle rising and falling movement given thereto by the gradual rise and fall of the water in the said upper compartment 26, thus insuring practically a noiseless operation of the valve or trap so far as concerns 40 the float. The upper end of the float 38 has attached thereto a guide pin or stem 39, with an axial passage 40 therethrough, and, as shown, this guide pin is attached to the float by threading its lower end into a block 45 or nut 41 attached to the inner face of the float, but can be otherwise attached to the float. The passage 40 furnishes communication between the upper compartment 26 and the interior of the float, by which air can 50 vent from the compartment 26 into the interior of the float 38 to be discharged therefrom.

The lower end of the float 38 has attached thereto a guide pin or stem 42, with an axial 55 passage 43 therethrough, which passage 43 is, as shown, of larger diameter than the passage 40 of the guide pin or stem 39 to insure a free discharge of air from the interior of the float. The guide pin 42 is attached to the float by threading its upper 60

end into a block or nut 44 attached to the inner face of the float, but can be otherwise attached. The guide pin 42 enters and is free to move up and down in a hole or guide-way extending into the plug 32 and terminating at the lower edge of the passages 36, in the arrangement shown; and the lower end of the guide pin 42 has a seating face 46 to coact with a seating face 47 around the upper end of the passage 37, 75 so that the guide pin 42 serves as a valve for controlling the outlet from the compartment 25, by opening and closing the passages 36 to allow water to discharge from the compartment 25 and to shut off 80 the outflow of water from such compartment, in the operation of the valve or trap.

The upper end of the shell or casing 13 is closed by a cap 48 having a depending flange 49 with an exterior screw thread, 85 which threads into the end of the outer shell or casing and having also a peripheral or lateral flange 50 which, when the cap is in place, abuts closely against the outer edge of the shell or casing. A plug 51 having 90 a threaded end 52 is entered into the cap 48, in the construction shown, and has a hole or guideway 53 to receive the upper guide pin 39 of the float 38, so that the float is free to play up and down and is guided 95 and held in its movements by the upper guide pin 39 moving in the hole 53 and the valve pin 42 moving in the hole 45.

The valve or trap of the present invention is readily and quickly assembled, it 100 only being necessary to thread the plug 32, with the cross-plate 27 attached thereto, into the bottom wall 20, thus dividing the interior of the shell or casing into communicating upper and lower compartments, then 105 enter the float 38 into the upper compartment with the guide and valve pin or stem 42 in the hole 45, and finally threading the closing cap 48, with the plug 51 in place, into the upper end of the shell or casing, 110 for the upper guide pin 39 to enter the hole 53, thus completing the assembling of the valve or trap. The coupling nut 15 and nipple or tail piece 18 can then be attached 115 to the neck 14, completing the valve or trap ready for use.

In use the valve or trap is attached to the radiator or other heating unit by unscrewing the coupling nut 15 and threading the coupling nipple 18 into the radiator or heating unit, attached to the return pipe or other discharging means by the threaded hole 22 of the neck 21. The water of condensation accumulating in the radiator or heating unit flows out therefrom through 120 the passage 19 of the coupling nipple or tail piece 18, and is conducted by the passage 23 into the lower compartment or chamber 25 in which it rises and enters the upper compartment, passing from below to above 125 130

the horizontal cross-plate, 27, either through the holes or perforations, or around the peripheral edge of the plate, and gradually rises in the upper compartment 26, until it reaches the floating point for the float, when the float will rise unseating the valve pin 42 and opening the outlet or discharge ports 36 and 37 for water to escape or discharge from the lower compartment through the outlet or discharge ports and allowing water to pass back from the upper compartment 26 into the lower compartment 25, and such outflow or downflow of the water in the compartment 26 will be gradual, allowing the float to descend and through the valve pin 42 close the outlet or discharge ports 36 and 37 and stopping the discharge of the water from the compartment 25.

It is to be noted that the effective and positive operation of the float, under practically the same rise and fall of the water in the float chamber, is attained by the cross-plate, which holds the water back against any sudden and rapid inflow into the float chamber and likewise prevents any rapid and forcible outflow from the float chamber. It is also to be noted that the sole discharge for the water of condensation is from the lower water receiving and discharging chamber, and that the outflow from the float chamber is in the nature of a drain off into the water discharging from the water receiving and discharging chamber and is not a direct discharge through the discharge ports of the discharge plug from the float chamber. It is further to be noted that the valve or trap is not wasteful of steam, as the water in the inlet and the lower compartment furnishes a dam against the ready passage of steam, and any steam passing the dam will be diffused by its passage above the cross-plate, and will be still further condensed and diffused in its passage through the water in the upper compartment, with the result that but little, if any, steam will enter the interior of the float through the upper guide pin, leaving the float perfectly free and clear to discharge the air. It is further to be noted that the valve or trap can be easily and quickly cleaned from any accumulation of oil, dirt or sediment in the water receiving and discharging chamber, it only being necessary to remove the float and blow off the oil, dirt and sediment through the discharge passage in the plug, and such operation is facilitated by locating the lateral passage near the inner face of the bottom wall of the shell or casing, and after the trap or valve has been blown out, the float can be replaced and the valve or trap is again ready for use. The construction dispenses with the employment of any by-pass and valve for cleaning purposes. Furthermore the oil, dirt and sediment will remain in the lower compartment and not pass to any great extent into the

upper compartment, and adhere to the float and wall of the upper compartment with the result that the upper compartment and the float are comparatively clean at all times, which is a distinct advantage in the operation of the valve or trap. 70

I claim:

1. In a valve of the class described, the combination of a shell or casing consisting of a chambered body portion merging into an enlarged chambered base portion, an inlet and an outlet for water of condensation located in the base portion, a member dividing the interior of the casing into an upper compartment and a lower compartment and formed to provide a communicating passage between said compartments for the water of condensation, a float in the upper compartment, a valve carried by the float and controlling the outlet, and the walls of said body portion continuing into said base portion and forming a weir surrounding said dividing member, and means for venting air from the casing, substantially as described. 80

2. In the valve of the class described, the combination of a shell or casing consisting of a chambered body portion merging into an enlarged chambered base portion, an inlet and an outlet for the water of condensation formed in the base portion, means for dividing the interior of the casing into an upper compartment and a lower compartment, said means being formed to provide a communicating passage between said compartments for the water of condensation, a float in the upper compartment, a valve carried by the float and controlling the flow of water from the interior of said casing to the outlet, and a depending wall in the interior of said base portion forming a weir surrounding the dividing means, that portion of the base chamber lying above the lower edge of said weir constituting an air chamber within said base portion, substantially as described. 90

3. In a valve of the class described, the combination of a shell or casing consisting of a chambered body portion merging into a chambered base portion, the chamber of said base portion being of greater width than the chamber of the body portion, means dividing the interior of the casing structure into an upper compartment and a lower compartment, said means being formed to provide a communicating passage between said compartments for water of condensation, a float in the upper compartment, an inlet and an outlet for the water of condensation in the lower compartment, a valve carried by the float and controlling communication between the interior of the casing structure and the outlet, a weir depending in the chamber of the base portion and spaced away from the side walls thereof, that portion of the chamber of the base portion ly- 110
115
120
125
130

ing above the weir constituting an air chamber and the point of communication between the chamber of the base portion, and the outlet being approximately flush with the floor line of the base portion, substantially as described.

4. In a valve of the class described, the combination of a shell or casing having an inlet and an outlet for water of condensation, a horizontal cross plate dividing the interior of the shell or casing into an upper compartment and a lower compartment, a float within the upper compartment, said plate being adapted to furnish a direct vertical communicating passage between the two compartments and having a line of communication in a plane outside of a vertical plane coincident with the exterior of the float within the upper compartment to prevent direct impact of the water against the bottom of said float, the inlet of the shell or casing opening into the lower compartment, a plug having a water discharge passage opening direct into the lower compartment and controlled by the rise and fall of the float in the upper compartment, and means for venting air from the casing, substantially as described.

5. In a valve of the class described, the combination of a shell or casing having an inlet and an outlet for water of condensation, a horizontal cross plate dividing the interior of the shell or casing into an upper compartment and a lower compartment, a float within the upper compartment, said plate presenting an imperforate body below the bottom of the float and having a configuration furnishing a direct vertical passage of communication between the two compartments in a plane outside of a vertical plane coincident with the exterior of the float, said communicating passage constituting a passage for water of condensation between the compartments for water to enter the upper compartment without direct impact against the bottom of the float, said casing being provided with a water discharge passage communicating with the outlet for the water of condensation and with the lower compartment of the shell or casing, said passage being controlled by the rise and fall of the float in the upper compartment, and means for venting air from the casing, substantially as described.

6. In a valve of the class described, the combination of a shell or casing having an inlet and an outlet for water of condensation, a horizontal cross plate dividing the interior of the shell or casing into an upper compartment and a lower compartment, a float within the upper compartment, said plate having a notched outer edge providing a direct vertical passage for water of condensation between the upper compartment and lower compartment, said passage being

located in a plane outside of a vertical plane coincident with the exterior of the float, and said plate presenting an imperforate body below the float, said casing being provided with a water discharge passage and communicating with the outlet for the water of condensation and with the lower compartment of the casing, said passage being controlled by the rise and fall of the float in the upper compartment, and means for venting air from the casing, substantially as described.

7. In a valve of the class described, the combination of a shell or casing having an inlet and an outlet for water of condensation, said outlet being located approximately flush with the lowermost floor line of the casing, a cross plate dividing the interior of the casing into an upper compartment and a lower compartment, a float within the upper compartment, said cross plate being formed to provide a direct vertical communicating passage between the upper and lower compartments, said passage being located in a plane outside of a vertical plane coincident with the exterior of the float, a valve carried by the float and directly controlling said outlet, and means for venting air from the casing, substantially as described.

8. In a valve of the class described, the combination of a shell or casing consisting of a chambered body portion having an inlet and an outlet for water of condensation formed in the base portion thereof, a horizontal plate dividing the chamber of the casing into an upper compartment and a lower compartment, said plate being formed to provide a communicating passage between said compartments for water of condensation, a float in the upper compartment, a valve carried by the float and controlling the passage of water from the interior of the casing into the outlet, and a depending wall in the plane of the body wall extending into the base portion of the shell or casing and forming a surrounding weir for the lower compartment of the casing, substantially as described.

9. In a valve of the class described, the combination of a shell or casing having an inlet and an outlet for water of condensation, a horizontal cross plate dividing the interior of the shell or casing into an upper compartment and a lower compartment, the lower compartment being in communication with the inlet and the outlet, a float located in the upper compartment and of a less cross area than the cross area of the upper compartment leaving a water space surrounding the float, said cross plate having a formation and arrangement furnishing adjacent to its periphery a direct vertical passage for water between the two compartments, such water passage being located

in line with the water space surrounding the body of the float with the body of the cross plate imperforate inside of the water passage, and protecting the bottom of the float against direct impact from the inflowing water, said casing being provided with a water discharge passage in communication with the outlet for the water of condensation and with the lower compartment, said

water discharge passage being controlled by 10 the rise and fall of the float, and means for venting air from the casing, substantially as described.
